INTERNAL COMBUSTION ENGINE

Lionel M. Woolson, deceased, late of Detroit, Mich., by Emma F. Woolson, executrix, Bloomfield Village, Mich., assignor to Packard Motor Car Company, Detroit, Mich., a corporation of Michigan

Application October 25, 1930, Serial No. 491,253

8 Claims. (Cl. 123—139)

This invention relates to internal combustion engines and more particularly to engines of the solid fuel injection type.

In engines of the compression-ignition type in which oil is injected into compressed air in the cylinders to form the fuel charges, it is important that the oil be introduced in a timed relation with the piston position on the compression strokes in order to obtain the greatest efficiency and thereby prevent a smoky exhaust, and I have found that the timing must therefore be varied in a definite relation with the regulation of the oil charge quantity to give the best combustion results.

It is a general object of the present invention to provide a novel and improved form of internal combustion engine.

More particularly it is an object of the invention to provide in an oil injection internal combustion engine of the radial cylinder type a novel mechanism for regulating the quantity of the oil charges and the time of their introduction into compressed air charges in the cylinders.

Another object of my invention is to provide a fuel charge control mechanism for engines wherein the manipulation of the fuel charge control will simultaneously vary the volume of the oil charges and the time of their introduction into the cylinders in a relative manner such that the greatest efficiency will result throughout the fuel range.

A further object of my invention is to regulate the timing of the introduction of oil charges into compression-ignition engines so that smoke will be eliminated from the exhaust.

These and other objects of the invention will appear from the following description taken in connection with the drawings, which form a part of this specification, and in which:

Fig. 1 is a rear end elevational view of a radial internal combustion engine, partly broken away and partly in section to illustrate the fuel injection mechanisms;

Fig. 2 is an enlarged view of one of the fuel push rod actuating rock levers and a fragment of the actuating cam enlarged and shown in two of its positions;

Fig. 3 is a vertical sectional view of the engine;

Fig. 4 is a sectional view taken on line 4—4 of Fig. 1 showing the mounting of one of the fuel push rod actuating rock levers;

Fig. 5 is an enlarged sectional view of the regulating mechanism for the control links;

Fig. 6 is sectional view of the control mechanism taken on line 6—6 of Fig. 5;

Fig. 7 is a plan view of the control mechanism for the regulating linkage.

In the drawings there is illustrated a radial internal combustion engine of the compression-ignition type operating preferably upon the four-stroke cycle principle and designed particularly for use as the power plant of an airplane. The barrel-like crank case 10 is provided with a plurality of apertures through which the radially extending cylinders 11 project, the cylinders having flanges 12 which bear against the outer face of the crank case to support them in position. A pair of circular band members 13 extend around and engage the flanges 12 and are placed in an initial tension greater than that developed therein by the explosion forces when the engine is operating. The crank case includes a pair of transversely extending reinforcing walls 14 and the rear end of the crank case is closed by an end wall 15.

The crank shaft 16 extends through the crank case and is mounted in bearings 17 carried by the walls 14, and at the forward end of the crank shaft a propeller (not shown) is arranged to be driven. A master rod 18 is carried by the crank shaft pin, and pistons 19 are connected to the master connecting rod and to the connecting rods 20 which are pivoted around the hub of the master rod.

Each of the cylinders is provided with an integral head 21 and with an auxiliary head 22, there being a neck portion 23 on the auxiliary head having a Venturi passage 24 which extends therethrough and through the end wall 21 of the associated cylinders to serve as both the air inlet and the exhaust outlet. A valve 25 is associated with the inner end of each Venturi passage, being normally maintained in closed position by a plurality of springs 26 and mechanically opened by the rock lever 27 actuated by the push rod mechanism 28 which extends within the crank case and engages a slipper 29. The valve actuating mechanisms are arranged to hold the valves open during the exhaust and intake strokes of the pistons and the valves are held closed by the springs during the compression and working strokes of the pistons. Air drawn into the cylinders through the Venturi passages during the suction strokes of the pistons is compressed during the compression strokes of the pistons and liquid fuel is sprayed into the compressed air charges during

ing the compression strokes by injection devices associated, preferably, one with each cylinder.

The injection devices are similar and include 5 a nozzle portion 30, which is secured to its associated engine cylinder by bolts 31, and a pump section. The pump section includes a casing 32 carrying a barrel 33 in which the plunger 34 reciprocates. A collar 35 is secured around each 10 of the barrels and provides a manifold for feeding fuel to the nozzle through the ports 36 when they are uncovered by the plunger 34, such adjacent manifolds being connected by conduits 37. A suitable system is associated with the conduits and manifolds to maintain a supply of fuel 15 oil under low pressure therein so that whenever the plungers uncover the ports 36 oil will flow into the nozzles and pump barrels to maintain them filled beyond the space occupied by the 20 plungers. Each plunger is moved in its injection stroke by a push rod 38 which engages therewith and is moved in the opposite direction by the coil spring 39 arranged intermediate the pump casing and the barrel.

A dual cam 40 telescopes the rear end of the 25 crank shaft 16 and is secured thereon by a retainer 41 which is fastened in any suitable manner, and on the periphery of such cam is provided two sets of lobes, the lobes of one set being indicated by the numeral 42 and the lobes of the other set being similar and indicated at 30 43 in Fig. 3. This cam is driven through reduction gearing from the crank shaft and such mechanism includes the gears, 44, 45, 46 and 47. 35 There are preferably nine cylinders and, therefore, nine valve mechanisms and injection devices. The push rods of each of the valve actuating mechanisms and the fuel injection devices extend interiorly of the crank case and are arranged in a plane so that they will be actuated 40 by the two sets of lobes on the cam 40. Looking at the rear end of the engine, the crank shaft is rotated in a clockwise direction and, consequently, the cam 40 will rotate in a counter-clockwise direction and the lobes of the cam are 45 engaged by the rock levers 29 which are associated one with each of the valve mechanism push rods and the rock levers 48 which are associated one with each of the push rods of the 50 fuel injection devices. The engine so far described forms the subject matter of my Patent No. 1,896,387 of February 7, 1933, and reference may be had thereto for a more complete description of the specific elements herein referred to.

It is the main purpose of this invention to 55 provide mechanism for controlling the time of the fuel charge injections and the quantity thereof and I have associated with the rock levers 48 a novel form of mechanism for accomplishing such result wherein the timing varies in a predetermined relation with the variance of the volume of the fuel charges. Shafts 49 extend between the rear reinforcing wall 14 and the rear cover plate 15 in a position to support the rock levers 48 and 29. One end of each rock lever 48 is formed as a sleeve and is mounted upon an eccentric 50 which is rotatably carried upon the shaft 49, while the other end is provided with a pocket 51 into which the end of the 60 associated push rod 38 is seated. The eccentrics are each formed preferably with an integral T-arm 52 which extends therefrom and the T-ends of such adjacent arms are connected by links 53, such links being pivoted at each 65 end as indicated at 54 to one end of adja-

cent T-arms. Between two of the T-arms, and preferably remote from the regulating mechanism indicated generally at 55, is provided a coil spring 9 designed particularly to take up any slack in the linkage connecting the T-arms and to prevent circular movement of the linkage in either direction which would normally tend to change the position of the linkage and, consequently, the adjustment of the rock levers and the consequent volume and timing of the fuel 10 charges.

It will be seen that the T-arms and the connecting links provide a connected substantially circular articulated regulating mechanism for the mounting of the slippers and I provide control 15 mechanism for moving the linkage circularly in either direction through multiplied motion. This control mechanism includes a cup-shaped casing member 56 which has a tubular extension which engages against the outer face of the crank 20 case 10 and is secured thereto by a sleeve 51, projecting through an opening 58 and formed with a flange engaging the interior face of the casing, and a nut 59 which is screwed upon the outer threaded end of the sleeve to clamp 25 against the shoulder portion of the cup-shaped casing. The bell crank lever 60 is pivoted at 61 to a bracket 62 which extends from the inner end of the sleeve 57, and one end 63 of the bell crank lever is pivotally connected to one of the 30 T-arms of the regulating mechanism through means of the link 64. A link 65 is pivoted to the arm 66 of the bell crank lever by a pin 66' and is also pivoted to the inner end of a sleeve 67, which partly telescopes within the sleeve 57, 35 by a pin 67'. It will be seen that axial movement of the sleeve 67 will be transmitted to the link 65 which will rock the bell crank lever 60 upon its pivotal mounting 61, and the bell crank in turn will move the link 64 in a direction to cause 40 the linkage to travel in substantially a circular direction, either clockwise or counterclockwise. The T-arms are rocked upon the shafts 49 upwardly or downwardly in accordance with the 45 direction of movement of the link 64 and the range of the pivotal movement of the T-arms is preferably substantially 120°.

In order to move the sleeve 67 axially, I provide the inner wall of the outer casing end with internal right-hand worm threads 68 and the outer head 69 of the sleeve 67 with worm threads 70, and intermediate the threads 68 and 69 I provide a cap 71 having external worm threads 72 meshing with the internal threads 68 and with interior left-hand worm threads 73 meshing with the threads 70 and the sleeve head 69. The pitch of the right-hand threads 68 and the left-hand threads 73 is the same so that the sleeve 67 will be moved twice as fast axially as the cap 71 moves when rotated by the arm 74. 50 The sleeve 67 is provided with a keyway 75 into which extends the key 76 which is seated within a slot 77 formed in the extension of the sleeve 57. By means of this key connection, rotation of the sleeve 67 is prevented and its movement is only a reciprocating one. It will be seen that the differential threads will multiply the axial movement of the cap 71 when rotated through the sleeve 67 to the bell rank 60 and in this manner only a small amount of cap rotation is 55 required in order to move the regulating mechanism within its range of adjustment. Suitable linkage (not shown) can be associated with the arm 74 for rotating the cap member 71 from a remote point.

The rock levers 48 and their eccentric mounting are of such a nature that there is a predetermined relation between the time of the fuel charge injections and the volume of the charges, 5 and this relation is preferably one whereby the timing will be most advanced during the cruising fuel charge volume range and more retarded when the fuel charge control is adjusted wide open or for idling. As the engine is designed preferably for use with aeroplanes, the 10 cruising range is ordinarily employed during the greatest portion of the engine operation; and it is during this range that I desire the fuel to be admitted the earliest so that there 15 will be the greatest length of time provided for the proper mixing of the fuel charge with the compressed air charge rotating within the cylinder, because I have found that if there is not sufficient time allowed for this mixture the 20 combustion is not complete and a smoky exhaust results. By this method of timing during the cruising range fuel adjustment, I provide complete combustion, which results in maximum efficiency of the engine, and eliminates objectionable smoke in the exhaust.

As shown in Fig. 3, the movement of the pump plunger 34 after closing the ports 36 determines the quantity of fuel which is forced from the nozzle into the cylinder, and by regulating the 30 range in which the plunger operates I am able to vary the volume of the fuel charges. It will be understood that when the pump plunger movement is adjusted so that it does not close the ports 36 in its outermost position, then no fuel 35 oil will be forced from the nozzle. Through the adjustable relation of the eccentrics 50 upon the stationary shafts 49, the rock levers will be positioned so that the quantity in the fuel charges injected and the time of injection into 40 the cylinder relative to the position of the pistons during the compression strokes can be varied. As shown in Fig. 2, rotation of the eccentric 50, through movement of the arm 52 in an outward direction, will shift the axis upon which 45 the rock lever pivots a desired degree to effect the cam contact with the rock levers to result in the desired fuel volume and the timing of the injection.

As shown in full lines in Fig. 2, the rock lever 50 48 is in a position such that a maximum quantity of fuel will be injected upon contact therewith of the cam lobes 42, and when in this position the eccentric center is indicated at A and the heel portion of the rock lever is in its most 55 retarded position with respect to the actuating face of the cam lobes which are moving in a counter-clockwise direction. In order to reduce the engine speed the arms 52 are moved outwardly thus shifting the axis of the eccentric 50 60 in the direction of the point indicated at B and when the eccentric is between the points A and B, a sufficient quantity of fuel will be injected to cause an aeroplane driven by the engine to be driven at cruising speeds. It will be seen 65 that upon movement of the eccentric from the position shown in full lines toward the position in which the axis will be at the point B, then the pivotal point of the rock lever is moved in a lengthwise direction, opposite to the direction 70 of the cam rotation, and is moved outwardly from the axis of the cam, thereby causing the plunger stroke to operate in a range closer to the crank shaft and thereby reducing the stroke after the ports 36 have been closed. In 75 this manner the quantity of the fuel charge is

reduced from what it is when the rock lever is in the position shown in full lines in Fig. 2. The point D indicates the outermost position to which the axis of the cam 50 can be moved by outward movement of the arm 52, and when the eccentric axis is in this position the stroke imparted to the plunger by the rock lever movement is not sufficient to close the ports 36, therefore the fuel injections are shut off. When the axis of the eccentric 50 is adjusted to lie in a line between the points C and D, the stroke imparted by the rock lever to the plungers will cause a fuel charge volume to be delivered which will result in idling engine speed and when such adjustment has been made the time of fuel delivery is retarded beyond that resulting when the eccentric axis is at the point B. This retarded timing is due to the changed angular position of the rock lever wherein the pivoted end is moved outwardly of the cam and, therefore, the rock lever heel or cam contacting point is engaged further up on the effective face of the cam lobes. The structure, herein shown, is of a character such that when a full fuel charge is being delivered, the injection into the cylinders takes place when the piston is in a position approximately thirty-eight degrees before top center on its compression stroke and when the eccentric axis is between the points C and D, the injection takes place approximately thirty-five degrees before the piston reaches top center on its compression stroke. When the eccentric axis is adjusted between the points A and B, then the fuel injections take place approximately forty-five degrees before the piston reaches top center position on the compression stroke.

It will be seen, therefore, that when the engine is running at a cruising speed the time of the fuel injections will be more advanced than when maximum injections are being delivered or when injections to cause idling speeds are being delivered. With advanced timing for cruising speed injections, greater time will be allowed for the oil charges to mix with the compressed air charges in the cylinders and the mixture constituents will have a longer time to intermingle and vaporize so that it is in much better condition for combustion than if the charges were delivered at a later time. As aeroplane 50 engines run at cruising speeds substantially all of the time while in the air, it is therefore important that some provision of this character be made if engine efficiency is to result and further because if engine efficiency does not result, then the incomplete combustion issues as an objectionable smoky exhaust; but with the regulating mechanism herein described, the maximum efficiency is obtained in the cruising speed and therefore a smoky exhaust does not result. In addition to providing a regulating mechanism which obtains the maximum efficiency and eliminates smoking during cruising speeds, the regulating mechanism described provides an efficient manner of controlling the 55 fuel injection devices.

The retarded injection timing of maximum fuel charges provides for lower peak pressures in the cylinders than would otherwise be present and thus the engine can be constructed of 60 a lighter weight material and withstand the operating explosion pressures.

While I have herein described in some detail a specific embodiment of my invention, which I deem to be new and advantageous and may 75

specifically claim, I do not desire it to be understood that my invention is limited to the exact details of the construction, as it will be apparent that changes may be made therein without departing from the spirit or scope of my invention.

What I claim is:

1. Fuel injection mechanism for internal combustion engines comprising a barrel having fuel inlet ports, a plunger in the barrel adapted to close the ports and to discharge trapped fuel under high pressure, an engine driven cam, actuator mechanism intermediate the plunger and the cam including a rock lever, a shaft, an eccentric member rotatable on the shaft, said rock lever being pivotally mounted on said member, and an actuator operable to rotate the eccentric member in a limited range of movement to regulate the rock lever position and thereby control both the volume and the time of fuel discharge from the barrel, said eccentric member being associated with the rock lever whereby an intermediate position of said member in its range of rotation will place said rock lever in a position so that the effective stroke of the plunger effects a smaller fuel volume injection than maximum and at the most advanced time in the range of adjustment.
2. Fuel injection mechanism for internal combustion engines comprising a barrel having fuel inlet ports, a plunger in the barrel adapted to close the ports and to discharge trapped fuel under high pressure, an engine driven cam, actuator mechanism intermediate the plunger and the cam including a pivoted lever, and means for shifting the position of the lever pivot eccentrically relative to the cam, said lever when in an intermediate position of its adjustment regulating the plunger stroke so that it injects less than maximum fuel volume at the most advanced time in the range of adjustment.
3. Fuel injection mechanism for internal combustion engines comprising a barrel having fuel inlet ports, a plunger in the barrel adapted to close the ports and to discharge trapped fuel under high pressure, an engine driven cam, push rod means associated with the plunger, an actuator element between the cam and the push rod means, and means for adjusting said actuator element laterally relative to the push rod and radially relative to the cam to regulate the effective plunger stroke and the timing thereof, an intermediate position of the element in its range of adjustment causing less than maximum effective injection strokes of the plunger and at the most advanced time in the range of adjustment.
4. Fuel injection mechanism for internal combustion engines having a plurality of cylinders comprising a fuel injection device of each cylinder including a ported barrel and a pump plunger in the barrel adapted to close the ports and discharge trapped fuel under high pressure, engine driven cam means, actuator mechanism intermediate each plunger and the cam means including a rock lever, a shaft adjacent each actuator mechanism, a member having an eccentric portion rotatably mounted on each shaft, the rock lever of the adjacent mechanism being mounted on the eccentric portion of the member, an arm fixed to each member, link means

connecting the adjacent arms, and means connected to one of the arms engageable to oscillate such arm.

5. In a radial cylinder internal combustion engine having a fuel injection device associated with each cylinder including a ported pump barrel and a pump plunger in each barrel which serves to shut off incoming fuel and to discharge trapped fuel under high pressure and an engine driven cam, actuator mechanism adjacent each plunger and the cam comprising a rock lever, a rotatably mounted eccentric member adjacent each actuator mechanism, each rock lever being mounted on the adjacent eccentric member, an arm fixed to each member, a coil spring connecting two adjacent arms, link means between the other adjacent arms, and means fixed to one of the arms operable to oscillate the associated eccentric member, the other arms being oscillated with the arm with which the operating means is associated through means of the linkage means and the spring.

6. In a radial internal combustion engine having circularly disposed fuel injection pump mechanisms associated one with each cylinder and each including a rock lever, fuel control mechanism comprising a rotatably mounted eccentric for each rock lever, said eccentrics being circularly disposed relatively, a radially extending arm fixed to each eccentric, means connecting the arms, and actuating means connected to oscillate one of the arms.

7. In a radial cylinder internal combustion engine having circularly disposed fuel injection pump mechanism associated one with each cylinder and each including a rock lever, fuel control mechanism comprising rotatably mounted eccentrics on which the rock levers are mounted, said eccentrics being circularly disposed, an arm fixed to each eccentric, resilient means connecting a pair of adjacent arms, link means connecting the other adjacent arms, and actuator means connected to oscillate one of the arms.

8. In an internal combustion engine having a plurality of radially disposed cylinders, a fuel injection device associated with each cylinder including a ported pump barrel and a plunger in the barrel which serves as a valve to cut off fuel supply and to discharge trapped fuel under high pressure, and an engine driven cam, actuator mechanism intermediate each plunger and the cam comprising an adjustable portion adapted to regulate the stroke of the mechanism, an eccentric member rotatably mounted adjacent each actuator mechanism, the adjustable portion of the actuator mechanism being connected to the adjacent eccentric member, a radially extending arm fixed to each of the eccentric members, a coil spring connecting two adjacent arms, circularly disposed means connecting the two arms with the other arms, and means connected with one of the arms for oscillating the associated eccentric member and the other eccentric members through the circularly disposed connecting means and the spring.
